UNITED STATES PATENT OFFICE.

PHILIPPE DE CLAMECY, OF CHARLESTOWN, MASSACHUSETTS, ASSIGNOR TO CORONA TYPEWRITER COMPANY, INC., OF GROTON, NEW YORK, A CORPORATION OF NEW YORK.

FOLDABLE TYPE-WRITING MACHINE.

1,294,060.

Specification of Letters Patent. Patented Feb. 11, 1919.

Application filed March 2, 1917, Serial No. 152,014. Renewed December 31, 1918. Serial No. 269,169.

To all whom it may concern:

Be it known that I, PHILIPPE DE CLAMECY, a citizen of the United States, and residing in Charlestown, county of Suffolk, 5 and State of Massachusetts, have invented certain new and useful Improvements in Foldable Type-Writing Machines, of which the following is a full, clear, and exact description.

10 One of the principal objects of this invention is to provide a typewriting machine with a keyboard wherein the key bars are arranged for a lateral swinging movement to bring said bars substantially parallel with the axis of the platen, in order to make the machine more compact.

Another object of the invention is to provide a keyboard wherein the key bars may be divided into two groups separating along 20 the central line of the machine, one group being arranged to swing toward the left and the other toward the right to bring the key bars into a position substantially parallel with the axis of the platen, to make the machine more compact.

25 A further object of the invention is to provide means whereby upon moving the key bars into their folded position substantially parallel with the axis of the platen, the platen carriage will be moved forwardly, whereby the length of the machine fore and rear will be very materially reduced and the machine made more compact.

30 There are other objects of the invention which will appear more fully hereinafter, all of them however, resulting in a typewriting machine adapted to be folded into a compact package for convenience in transportation and storage.

35 As illustrated in the drawings, the invention relates to a front strike visible typewriting machine of very light construction, and of few and simple parts.

In the drawings, Figure 1 is a longitudinal 40 vertical sectional view of the machine in its folded position;

Fig. 2 a similar view, showing the machine extended and in operative position;

Fig. 3 a detail sectional view, showing 45 one of the type bars and its supporting means;

Fig. 4 a plan view of the machine extended and in operative position;

Fig. 5 a plan view of the means for swing- 50 ing the key bars laterally and the platen

carriage forwardly to their folded or compact position;

Fig. 6 a detail plan view of a portion of the keyboard;

Fig. 7 a detail partial sectional view of 60 one end of the platen carriage;

Fig. 8 an end elevation of the parts shown in Fig. 7;

Fig. 9 a horizontal sectional view of one 65 of the standards carrying the platen, taken on the line IX—IX of Fig. 8;

Fig. 10 a horizontal sectional view on the line X—X of Fig. 8, the platen being omitted;

Fig. 11 a detail rear view of the carriage 70 rack and the escapement dog;

Fig. 12 a detail sectional view of the parts shown in Fig. 11;

Fig. 13 a detail of a portion of the ribbon 75 feeding mechanism;

Fig. 14 a vertical sectional view of one of the vertical posts in which the universal bar is supported;

Fig. 15 a detail elevation of the ribbon 80 guide and vibrator;

Fig. 16 a detail view of the means for positioning the key bars and for moving them into their folded position;

Fig. 17 a detail sectional view of a portion of the means for positioning the key 85 bars; and

Fig. 18 a detail view of one of the links of the key bar connecting means.

The machine when folded, is adapted to be contained within a rectangular box, composed of the base section *a*, the front section *b* hinged to the forward edge of the base section, and a partial cover section *c* hinged to the upper edge of the front section. The front section is adapted to be folded down 90 into the same horizontal plane as the base section and to form a portion of the base of the machine when it is extended into operative position. The part *c* of the cover may be folded under the front section *b*, as 95 illustrated in Fig. 2, or it may be permitted to remain in the same horizontal plane with the said front section and with the base section, if desired. To the rear edge of the base section is hinged a two part rear section *d* and *e*, said parts being hinged together at *f*. The part *d* is adapted to fold down into the plane of the base and to form a portion 100 of said base when the machine is in its extended position, as illustrated in Fig. 2. To 105 110

the upper edge of the rear section *e* is hinged to the rear of the section *e*, as shown in Fig. 2, when the machine is extended and in its operative position. It will, of course, be understood that there are side sections which, combined with the other parts of the inclosing box, as described herein, completely inclose the mechanism when in its folded and compact position.

The keyboard is made up of key bars 1, which carry at their forward ends, the usual upstanding keys. Each key bar passes through a vertically slotted post 2, and is pivoted at its rear end to the forward end 3 of the type bar operating link 4. The rear end of this link is connected to the forwardly extending arm 5 of a bell crank lever 6, the upper end of said lever being slotted at 7 to receive a pin 8 on the lower end of a vertically arranged type bar 9. This type bar carries the type block 10 at its upper end and is formed with a forwardly extending guide arm 11. This guide arm fits and slides in a guide tube 12, in which is arranged a coil spring 13, said spring normally acting to draw the type bar to its rearward position, as shown in Figs. 2 and 3. The type bar operating link 4 is pivoted on the bar 14.

Each key bar guiding post 2 is pivoted at its lower end to the ends of links 15, the other ends of said links being pivoted together at 16 in the form of lazy tongs. The forward ends of the links 15 are each provided with a forwardly projecting shoulder 17, said shoulders abutting together to limit the swinging movement of said links when the key bars are swung into their operative position, as illustrated in Figs. 1 and 6 of the drawings. The shoulders 17 insure the proper positioning of the key bars with respect to each other, while at the same time, permit said keys to be swung laterally to the right or to the left, as indicated in dotted lines in Fig. 6, the links 15 folding together as the links of a lazy tongs. The outer end links 15^a are provided at their rear ends with headed pins 18 which fit and slide in a groove 19 in the under side of the base *a* of the machine, as illustrated clearly in Figs. 16 and 17 of the drawings. The pin 18 extends upwardly through a slot 20 in the base, so that the end post 2^a carried by the end link 15^a will be caused to move outwardly and rearwardly in the slot 20, as will be hereinafter described. Mounted on the base of the machine are two forwardly extending levers 21, said levers being pivoted at 22, as shown clearly in Fig. 5. To the forward portion of each of these levers is connected the innermost posts 2^b, the said forwardly projecting portions of the levers 21 being arranged at the center line of the machine. The posts 2 are ar-

ranged in two groups, A and B, the outer post 2^a of group A being arranged to move in the slot 20 at the right hand side of the machine, the post 2^b of said group being mounted on the right hand lever 21. The post 2^a of the group B is mounted in the slot 20 at the left hand side of the machine and the inner post 2^b of said group is mounted on the left hand lever 21, as shown clearly in Fig. 5. When the levers 21 are moved outwardly and rearwardly to the position shown in dotted lines in Fig. 5, the links 15 collapse or swing into closer relation, and the posts 2^a move outwardly and rearwardly in the slots 20, the key bars swing outwardly or laterally with the posts, and finally assuming the position shown in dotted lines in Fig. 6. When the levers 21 are brought forwardly into the full line position shown in Fig. 5, the links 15 are extended or swung outwardly away from each other until the shoulders 17 abut together, thereby locking the links against further separating movement. The headed pins of the posts 2^a move forwardly and inwardly in the slots 20 to the position shown in Figs. 4 and 5, thereby limiting the movement of the key bars. It is therefore manifest that in order to collapse the keyboard and to bring the key bars into a substantially parallel relation with the axis of the platen it is only necessary to swing outwardly and rearwardly the levers 21 to the position shown in Fig. 5. The vertical slots in the posts 2 and 2^a permit of the vertical movement of the key bars during the printing operation. The key bars and type bars are returned to their normal position after the printing operation by the springs 13 and by the universal bar, as will be more fully hereinafter described.

The platen carriage 23 consists of a bed plate provided at its ends with ribs 24 which fit the slide in grooved supports and guides 25. These supports and guides are sectional, one part thereof being mounted on the base *a*, the other part being carried by the portion *d* of the rear wall of the box. When the machine is in its extended operative position the two portions of the guides are in the same horizontal plane as indicated in Figs. 5 and 8, and the carriage bed may then slide forwardly and rearwardly in said guides. The levers 21 are formed with rearwardly extending arms 26 which are connected by links 27 to the forward edge of the carriage bed, shown at 28 in Fig. 5. It is manifest that when the levers 21 are swung outwardly and rearwardly the links 27 and the carriage bed will be drawn forward into the position shown in dotted lines in Fig. 5, so that the carriage is wholly supported on the base portion *a* of the inclosing frame when the machine is in its compact or collapsed position. This frees

the portion of the guides 25 which are supported on the section *d* of the box or frame, so that said portion may be swung upwardly into the position shown in Fig. 1 when it is 5 desired to inclose the machine in its box.

On the carriage bed are secured transversely extending guides or tracks 29, which are grooved on their adjoining faces in order to receive the base 30 of the platen carriage 10 and to guide it in its transverse movement across the machine. As shown in Fig. 8 of the drawings, the base 30 is supported in position to move over the guides 25 in the lateral or transverse travel of the carriage. 15 Mounted on the upper side of the base of the carriage is a driving rack 31 with which engages a driving pinion 32, said pinion being driven through a spring drum 33 secured to the rear wall of the machine support. It 20 will, of course, be understood that the carriage may be driven or moved transversely of the machine by any suitable means.

The platen 34 is journaled in the upper end of vertically arranged posts 35, said 25 posts being provided with ribs on their vertical edges adapted to fit and slide in vertical grooves in the standards 36 of the carriage. The standards 36 are arranged near the ends 30 of the carriage base. The posts 35 are connected together below the platen by a pair 35 of horizontal rods 37 and 37^a, one of said bars being directly over the other, as indicated clearly in Fig. 1 of the drawings. At the outer end of each group of keys are arranged two platen shift keys 38 and 39, the 40 keys 39 being arranged to extend through the outer slotted posts 2^a, as shown clearly in Fig. 1. These shift keys are pivoted at their rear ends at 40 to the forward ends of the shift levers 41 and 42, each of which is in turn pivoted on a bracket 43. The pivots 40 correspond to the pivots 3 of the key bars and permit the shift keys to be swung laterally into parallel relation with the platen. 45 The rear arms or members 41^a of the levers 41 are longer than the rear arms 42^a of the levers 42 in order to provide for the two case movements or shifts of the platen. Connecting the rear ends of the arms 41^a and 42^a 50 with the transverse rods 37 and 37^a of the platen support are linked connections 44 and 45, 44 connecting the rear ends of the arms 41^a to the upper rod 37 by means of the bell crank lever 46. The linked connection 45 55 connects the rear end of the arms 42^a with the lower rod 37^a, as shown clearly in Figs. 1 and 2 of the drawings. The links which make up the connections 44 and 45 are formed with downwardly extending interlocking shoulders 47', so arranged that when the linked connections are raised through the shift keys said shoulders abut together and convert the linked connection into a substantially rigid bar which moves upwardly 60 under the action of the key levers. The pur-

pose of connecting the rear ends of the arms 41^a and 42^a with the platen support by means of the linked bars is to permit of the folding of the parts, as will be hereinafter described. To permit the platen carriage to be 70 moved forwardly into the position shown in Fig. 1, the platen must be bodily lifted in its support, in order to permit the linked bars 44 and 45 to be swung rearwardly of the bars 37, as shown clearly in Fig. 1. When the 75 said bars have been moved rearwardly sufficiently to permit the carriage bed to be drawn into its forwardmost position, the platen may then be dropped or lowered into the position shown in Fig. 1. When restoring the machine to its operative position, the 80 platen must first be lifted or raised in its supports to permit the linked connections to be restored to their operative positions, as shown in Fig. 2.

The paper guide 47 is carried by two grooved bars 48 which are rigidly connected to the inner sides of the platen supporting posts 35. It will be, of course, understood that any suitable form of paper guide and 90 support may be used.

The universal bar 49 is mounted on vertical rods 50 which are arranged in vertical posts 51, said universal bar overlying the shift levers and the type bars, as shown 95 clearly in Fig. 1. Springs 52 maintain the universal bar in its lowermost position and the type bars and shift levers lift said universal bar against the tension of said springs. On each of its ends the universal bar is extended upwardly and carries a pawl 53 which engages a ratchet 54 of a ribbon spool 55. These pawls may be arranged in any suitable manner and one may be thrown out of operation so that the ribbon will be 100 alternately wound on first one ribbon spool and then the other. The pawls and ratchets are so arranged that when the universal bar is raised the ribbon spool will be moved to take up the ribbon.

Connected to the universal bar and extending rearwardly therefrom are two arms 56, said arms at their rear ends carrying the upwardly extending ribbon guide 57, said guide being pivoted on the end bar 58 which 115 connects the rear ends of the arms 56. The ribbon guide 57 is held in proper position with relation to the platen by a spring 59 which is coiled about the rod 58, its ends engaging the ribbon guide, as clearly shown in 120 Fig. 15. It is manifest therefore, that the ribbon will be vertically vibrated through the movement of the universal bar. When the platen carriage is moved forward through the operation of the levers 21 the 125 ribbon guide will be swung forwardly and downwardly by the rod 37^a, as clearly shown in Fig. 1.

Extending rearwardly from the cross bar 58 is a lug 60, on which is pivoted an escape- 130

ment dog 61. On the carriage bed is secured an escapement rack 62. Coiled about the lug 60 is a spring 63, whose end engages the escapement dog and tends to throw the hooked end 64 down into engagement with the teeth of the escapement rack. The end 65 of the escapement dog is adapted also to engage in the teeth of the said rack. In its normal position the end 65 of the escapement dog is in engagement with one of the teeth of the escapement rack, and the end 64 thereof is at rest on the peak of another tooth of said rack, as shown clearly in Fig. 11. When the universal bar is operated the dog is bodily lifted and the spring 63 maintains the hooked end 64 of the dog in engagement with the rack and causes it to be engaged by the next tooth of the escapement rack, the said rack being driven in the direction indicated by the arrow in Fig. 11. When the universal bar is released the weight of the said bar and its connected parts and the tension of the springs 52 carry the escapement dog downwardly, bringing the point 65 into engagement with the rack. This will bring about a rocking motion of the dog, which will free the hook from the point of the tooth with which it is in engagement and permit the rack to have a slight additional movement to bring a tooth thereof into direct contact with the point 62, thereby permitting the hooked end 64 to rest upon the point or peak of the next tooth of the rack. In this way the step-by-step movement of the carriage for letter spacing will be obtained. Connected to the universal bar is a spring 66 which insures said bar returning into position to be engaged by the type bars and the shift levers, said spring being clearly shown in Figs. 1 and 2.

The space key 67 is made in four sections, the rearward rigid section 67^a being pivoted on the bar 14 and extending rearwardly under the universal bar, as shown clearly in Figs. 1 and 2. Secured to the upper edge of this section is a forwardly extending rigid arm 68 which overlies the pivot bar 14, as clearly shown in Fig. 2. Connected to the forward end of this bar 68, and to each other by pin-and-slot connections are three lever sections 67^b, the space key or finger piece being carried by the forwardmost section, as shown clearly in Fig. 2. When collapsing the machine, the members of the sectional key are slid rearwardly on each other to the position shown in Fig. 1. The space key is arranged at the center of the keyboard, as shown clearly in Fig. 4, the sectional members thereof being arranged between the posts 2^b, so that said key does not interfere with the lateral swinging movements of the two groups of key bars.

What I claim is:—

1. In a typewriting machine, key bars,

type bars operated thereby, a platen, and means for permitting the key bars to be swung laterally and rearwardly to be brought into approximately parallel relation to the axis of the platen.

2. In a typewriting machine, key bars, type bars operated thereby, a platen carriage, means for swinging the key bars laterally and rearwardly, and means to move the platen carriage forwardly to compact the machine.

3. In a typewriting machine, key bars, type bars operated thereby, and means to permit said key bars to be moved in groups laterally and rearwardly to compact the machine.

4. In a typewriting machine, key bars, type bars operated thereby, means to permit said key bars to be swung laterally and rearwardly to compact the machine, and means to connect said key bars together in groups, whereby the keys of each group will move together.

5. In a typewriting machine, key bars, type bars operated thereby, a vertical pivot at the rear end of each key bar, whereby said key bars may be swung laterally and rearwardly, and means for connecting said key bars together in groups.

6. In a typewriting machine, key bars, type bars operated thereby, a vertical pivot at the rear end of each key bar whereby said key bars may be swung laterally and rearwardly, means for connecting said key bars together in groups, and means for moving said groups of keys laterally and rearwardly at each side of the center of the machine.

7. In a typewriting machine, key bars, type bars operated thereby, a vertical pivot at the rear end of each key bar whereby said key bars may be swung laterally and rearwardly, means for connecting said key bars together in groups, and means for moving said groups of keys laterally and rearwardly at each side of the center of the machine, the group on the right being movable toward the right and rearwardly, the group on the left being movable to the left and rearwardly.

8. In a typewriting machine, key bars, type bars operated thereby, a vertical pivot at the rear end of each key bar whereby said key bars may be swung laterally and rearwardly, means for connecting said key bars together in groups, means for moving said groups of keys laterally and rearwardly at each side of the center of the machine, the group on the right being movable toward the right and rearwardly, the group on the left being movable to the left and rearwardly, a platen carriage, and means connecting each group of keys to the carriage, whereby said carriage will be moved forwardly when the groups of keys are moved rearwardly.

9. In a typewriting machine, a platen car-

riage, means for supporting said carriage to permit it to have a vertical shift movement, a shift key, a shift lever, the rear end of the shift key being pivoted to the forward end 5 of the shift lever to permit it to be swung rearwardly and laterally to compact the machine, and means connecting the rear end of the shift lever with the platen carriage.

10. In a typewriting machine, key bars, type bars operated thereby, a vertical pivot at the rear end of each key bar whereby said key bars may be swung laterally and rearwardly, means for connecting said key bars together in groups, means for moving said 15 groups of keys laterally and rearwardly at each side of the center of the machine, and a lazy tongs connecting together the keys of each group.

11. In a typewriting machine, key bars, type bars operated thereby, a vertical pivot at the rear end of each key bar whereby said key bars may be swung laterally and rearwardly, means for connecting said key bars together in groups, means for moving said 25 groups of keys laterally and rearwardly at each side of the center of the machine, and a lazy tongs connecting together the keys of each group, vertically slotted posts carried by the members of the lazy tongs and adapt- 30 ed to receive the key levers.

12. In a typewriting machine, key bars, type bars operated thereby, a vertical pivot at the rear end of each key bar whereby said key bars may be swung laterally and rearwardly, means for connecting said key bars together in groups, means for moving said 35 groups of keys laterally and rearwardly at each side of the center of the machine, a lazy tongs connecting together the keys of each group, vertically slotted posts carried by the members of the lazy tongs and adapted to re- 40

ceive the key levers, and means for limiting the outward swinging movement of the members of the lazy tongs.

13. In a typewriting machine, key bars, 45 type bars operated thereby, a vertical pivot at the rear end of each key bar whereby said key bars may be swung laterally and rearwardly, means for connecting said key bars together in groups, means for moving said 50 groups of keys laterally and rearwardly at each side of the center of the machine, a lazy tongs connecting together the keys of each group, vertically slotted posts carried by the members of the lazy tongs and adapted to 55 receive the key levers, and means for positioning said posts, and means carried by the members of the lazy tongs for positioning the keys with respect to each other in their operative position. 60

14. In a typewriting machine, key bars, type bars operated thereby, a vertical pivot at the rear end of each key bar whereby said key bars may be swung laterally and rearwardly, means for connecting said key bars 65 together in groups, means for moving said groups of keys laterally and rearwardly at each side of the center of the machine, a lazy tongs connecting together the keys of each group, vertically slotted posts carried by 70 the members of the lazy tongs and adapted to receive the key levers, means for positioning said posts, means carried by the members of the lazy tongs for positioning the keys with respect to each other in their operative 75 position, and means for collapsing the lazy tongs to move the key levers into their inoperative compacted position.

This specification signed this 26th day of February, A. D. 1917.

PHILIPPE de CLAMECY.
